UNITED STATES PATENT OFFICE

140,821

DESIGN FOR A HAMMER HEAD

Frederick L. MacWithey, Plymouth, Fla.

Application December 26, 1944, Serial No. 117,093

Term of patent 14 years

(Cl. D93—4)

To all whom it may concern:

Be it known that I, Frederick L. MacWithey, a citizen of the United States, residing at Plymouth, in the county of Orange and State of Florida, have invented a new, original, and ornamental Design for a Hammer Head, of which the following is a specification, reference being had to the accompanying drawing, forming part thereof.

Figure 1 is a face view of a hammer head showing my new design.

Figure 2 is an elevation of one end of the hammer head.

Figure 3 is a top plan view.

I claim:

The ornamental design for a hammer head, as shown.

FREDERICK L. MACWITHEY.
